UNITED STATES PATENT OFFICE.

JAMES SHEPHARD, OF DETROIT, MICHIGAN.

VACUUM GASOLENE FEED-TANK.

1,358,118.

Specification of Letters Patent.

Patented Nov. 9, 1920.

Application filed January 15, 1920. Serial No. 351,717.

To all whom it may concern:

Be it known that I, JAMES SHEPHARD, citizen of the United States, residing at Detroit, county of Wayne, State of Michigan, have invented a certain new and useful Improvement in Vacuum Gasolene Feed-Tanks, and declare the following to be a full, clear, and exact description of the same, such as will enable others skilled in the art to which it pertains to make and use the same, reference being had to the accompanying drawings, which form a part of this specification.

My invention relates to a vacuum gasolene feed tank, for motor driven cars, shown in the accompanying drawings and more particularly described in the following specification and claims.

One object of the present invention is an improvement in the general construction of tanks of this character, the same being relatively more simple in construction, less expensive to manufacture, and more efficient in its operation.

With the foregoing and other objects in view which will appear as the description proceeds, the invention resides in the combination and arrangement of parts and in the details of construction hereinafter described and claimed, it being understood that changes may be made in the precise embodiment of the invention herein disclosed without departing from the spirit of the same.

In the accompanying drawings forming part of this specification:—

Fig. 1 is a diagrammatic view showing a motor vehicle, an internal combustion engine, the intake manifold of the engine, carburetor, gasolene fuel tank, the vacuum feed tank, and the respective connections between the several parts.

Fig. 2 is a plan view of the vacuum feed tank attached to the dash or body of the vehicle.

Fig. 3 is a vertical cross-sectional view on line 3—3 of Fig. 2.

Fig. 4 is a fragmentary cross-sectional view on line 4—4 of Fig. 2, through the valves controlling the suction and air-vent pipes.

Fig. 5 is a vertical cross-sectional view through the tank with the float raised as when closing the suction cut-off valve and opening the air-vent valve that the fuel may pass to the lower tank through the discharge

valve which is opened when the float reaches a predetermined altitude.

Fig. 6 is a side elevation of the float and coöperating parts, with the float in its lowermost position, as when the upper tank is filling.

Fig. 7 is a side elevation of the float and coöperating parts, with the float in its elevated position as shown in Fig. 5.

Fig. 8 is an elevation of the float and co-operating elements viewed at right angles to Fig. 6, showing the discharge valve in section.

Referring now to the letters of reference placed upon the drawings:—

A, denotes an internal combustion engine, B, its intake manifold, C, a carburetor connected with the manifold. D, is a gasolene supply tank and E, indicates the dash of a motor vehicle.

F and F' denote a pair of super-imposed tanks secured to the dash or other support by clips f, bolted thereto.

G, is a pipe connection leading from the intake manifold B to a fitting having a port opening into the upper tank F, controlled by a valve H. I, indicates an air-vent for the upper tank controlled by a ball valve I', which is in turn raised from its seat by the thrust of an upstanding pin I², supported by a cross arm J, on which the valve H is also mounted.

K, is a guide rod having a limited vertical movement to which the cross arm J is secured.

L, is a float sleeved upon the guide rod K, which is adapted to raise the guide rod upon the gasolene attaining a sufficient altitude in the tank, due to the float contacting with the stop or abutment M, which is in turn secured to the guide rod. The lower end of the guide rod K projects into the body N, of the discharge valve controlling the discharge of gasolene into the lower gasolene tank F', through the pipe connection O. The discharge valve comprises a ball N' having an integral stem projecting through the inlet orifice of the valve body;—the pin being secured to a cross-bar N² secured to a vertical guide rod N³ extending through the valve body N and engaged to the projecting arm N⁴, which is in turn soldered or pinned to the guide rod K.

P, is a weighted lever pivoted at P' to a

- bracket carried by the valve body N, having a lug P² adapted to engage the projecting arm N⁴, when the float is in its elevated position. The free end of the lever P², extends 5 into the vertical path of the float that the latter may trip the lever and thus release the guide rod in order that the discharge valve may be seated to cut off the discharge of gasoline into the lower tank F', when the 10 altitude of the gasoline is low in the upper tank.

G, indicates an air vent pipe extending upwardly from the lower tank so that the latter tank may not be air bound when it is desired to discharge the fuel from the lower tank. R, is a fuel pipe leading from the lower tank to the carburetor c, which is in turn connected with the intake manifold B, of the engine. T is a drain-off plug in the 20 bottom of the upper tank F, and T' is a similar drain off plug from the lower tank F'. U, denotes a fuel pipe connection between the gasoline tank D and the upper tank F, under control of a ball check valve U', to 25 prevent the return of the fuel to the tank.

Having now indicated the several parts by reference letters, the construction and operation of the device will be readily understood:

30 The tank F being connected through the pipe G with the intake manifold B, the suction stroke of the engine induces a vacuum in the tank F thereby drawing gasoline from the supply tank D through the pipe U, and discharging it into the tank F;—the check valve U' serving to prevent the return of the gasoline to the tank. Upon the altitude of the gasoline in the tank F reaching a predetermined level the float L, rising 35 with the gasoline will engage the stop or abutment M, on the guide rod K, thereby causing the valve H connected with the rod K to seat, and thus cutting off the further delivery of gasoline to the tank.

40 45 Simultaneously with the seating of the valve H, the air vent or check valve I' is opened, due to the thrust of the pin I², which is also connected with the rod K. The vacuum in the tank being relieved by opening the valve I', the gasoline is free to flow by gravity to the tank F' through the pipe connection O, and the discharge valve N';—the latter being opened through its connection with the guide rod K by the cross bar N², vertical rod N³, and arm N⁴. The gasoline then passes from the tank F' by gravity to the carburetor through the pipe R.

When the level of gasoline in the tank F has become sufficiently low for the float L 50 to trip the weighted lever P, by bearing upon its free end P², the rod K, is released from the support afforded by the lug P², and descending opens the suction valve H that gasoline may be drawn into the tank F,— 55 the check valve I' being simultaneously

closed. It will thus be seen that gasoline is drawn from the storage tank D and delivered to the upper tank F passing thence to the lower tank F' and from the latter to the carburetor as consumed.

70

Should there be any tendency for the fuel supply to "back up" from the lower tank F', it will rise through the pipe connection O, into the tank F.

It will now be apparent that in the present invention the valve for closing the suction pipe from the manifold,—the air relief valve,—and the valve controlling the discharge of gasoline from the upper to the lower tank or chamber, are each positively held in their respective open or closed positions until the gasoline is lowered in the upper tank to a predetermined low level, whereupon an alternate positive action of the respective valves takes place to permit the upper tank to again fill, regardless of the suction created due to engines employing a relatively large number of cylinders;—it being well known that devices of this character employing swinging flap valves for controlling the discharge of gasoline from the upper to the lower tank are often held closed against the weight or pressure of the gasoline in the upper tank due to the suction created by engines having a large number of cylinders.

Having thus described my invention what I claim is:—

1. In a device of the character described, a gasoline tank comprising an upper and a lower chamber, a suction pipe for connecting the upper chamber with the intake manifold of an engine, whereby a vacuum is created in the upper chamber by the suction stroke of the engine, a valve for controlling said pipe, a valve for controlling the admission of air to the upper chamber, a fuel supply tank, a pipe adapted to connect the upper chamber with the fuel supply tank, a valve casing within the upper tank, a passage leading from said casing out through the wall of the upper chamber and communicating with the lower chamber to supply gasoline fuel to the lower chamber, a valve confined within said valve casing for controlling the delivery of gasoline between the upper and lower chambers, a pipe adapted to connect the lower chamber with the carburetor of an engine, a float adapted to simultaneously and alternately close the valve controlling the suction pipe and to open the valve controlling the admission of air to the upper chamber and also to open the valve controlling the delivery of gasoline from the upper to the lower chamber, when the gasoline in the upper chamber has reached a predetermined level, and means whereby the respective valves may be secured in their respective open and closed positions until the gasoline in the upper 120 125 130

chamber has been lowered to a predetermined level.

2. In a device of the character described, a gasolene tank comprising an upper and a lower chamber, a suction pipe adapted to establish communication between said upper chamber and the intake manifold of an engine, a valve for controlling the suction of the engine through said pipe, a valve for controlling the admission of air into the upper chamber, a fuel supply tank, a pipe adapted to connect the upper chamber with the fuel supply tank, a check valve for said last named pipe, a valve casing, a passage between the valve casing and the lower tank, a valve in said valve casing for controlling the delivery of fuel between the upper and lower chambers, a float housed in the upper chamber, and means simultaneously actuated by the float adapted to close and to maintain in a closed position the valve in the suction pipe, to open and to maintain in an open position the valve for controlling the admission of air to the upper chamber, and also to open and to maintain in an open position the valve controlling the delivery of fuel from the upper to the lower chamber upon the float attaining a predetermined high level in the upper tank, said means being adapted to be actuated by said float to release said valves that they may function in their normal positions upon the float descending through the discharge of the fuel to a predetermined low level.

3. In a device of the character described, a gasolene tank comprising an upper and a lower chamber, a suction pipe adapted to connect the upper chamber with the intake manifold of an engine, a valve for controlling the suction pipe, an air relief valve for the upper chamber, a fuel pipe for connecting the upper chamber with a fuel supply tank, a check valve for said fuel pipe, a passage between the upper and lower chambers, a valve confined within said passage for controlling the delivery of fuel from the upper to the lower tank, a rod having a limited vertical movement, plural means respectively connecting said rod with the valve for controlling the suction pipe, the air relief valve, and the valve controlling the delivery of fuel from the upper to the lower tank; a float

adapted to lift said rod, whereby the several valves may be simultaneously operated, means adapted to support the rod when raised by said float and to release said rod when tripped by the float upon its return to its former position.

4. In a device of the character described, a gasolene tank comprising an upper and lower chamber, a suction pipe connected with the upper chamber, a valve for controlling said pipe, an air relief valve for the upper chamber, means for delivering liquid fuel to the upper chamber, a passage for delivering the liquid fuel from the upper to the lower chamber, a valve controlling the delivery of the liquid fuel from the upper to the lower chamber, a rod having a limited vertical movement with which said valves are respectively connected for simultaneous operation, a float adapted to raise said rod, and a weighted lever adapted to support said rod when raised and to be tripped by the float upon the descent of the latter, whereby the valves may function in their respective adjusted positions.

5. In a device of the character described, a gasolene tank comprising an upper and a lower chamber, a valved suction pipe connected with the upper chamber, an air relief valve for the upper chamber, means for delivering liquid fuel to the upper chamber, a passage for delivering the liquid fuel from the upper chamber to the lower chamber, a valve controlling the delivery of the liquid fuel from the upper chamber to the lower chamber, a rod having vertical movement with which all of said valves are respectively connected for simultaneous operation, a float adapted to raise said rod, and means including a lever adapted to support said rod when the latter is raised and disposed in the path of the float to be tripped by the latter upon descent of the float, whereby the valves may function in their respective positions.

In testimony whereof, I sign this specification in the presence of two witnesses:

JAMES SHEPHARD.
